UNITED STATES PATENT OFFICE.

HUGO F. SPENGLER, OF CHICAGO, ILLINOIS.

AUTOMATIC STOP FOR PHONOGRAHS.

Application filed March 10, 1924. Serial No. 698,079.

To all whom it may concern:

Be it known that I, HUGO F. SPENGLER, a citizen of the United States, and a resident of Chicago, in the county of Cook and State 5 of Illinois, have invented certain new and useful Improvements in Automatic Stops for Phonographs; and I do hereby declare that the following is a full, clear, and exact description thereof, reference being had to 10 the accompanying drawings and to the letters of reference marked thereon, which form a part of this specification.

This invention relates to improvements in automatic stops for phonographs and consists of the matters herein described and more particularly pointed out in the appended claims.

The primary object of the invention is to provide a simple and efficient automatic device for stopping the rotation of the turn-table after the full playing of the record, and this without the necessity of manually setting the device before the playing of said record.

25 A further object of the invention is to provide an automatic stop device which is particularly adapted for use in connection with disc records of the kind wherein the last sound groove thereof terminates in an eccentrically disposed mute groove at the center of the record, which acts when reached by the stylus to cause the tone arm to oscillate horizontally to actuate the braking means for said turntable and stop the 30 rotation thereof.

These objects of the invention as well as the many advantages thereof will more fully appear as I proceed with my specification.

40 In the drawings:

Figure 1 is a top plan view of the motor board of a phonograph, with the turn-table and tone arm mounted thereon, a part of said motor board being shown as broken away to more clearly indicate the position of the parts embodied in my improved automatic stop;

Figure 2 is a detail vertical section on an enlarged scale through the braking part of 50 my improved stop device, the plane of the section being indicated by the line 2—2 of Fig. 1;

Figure 3 is a view similar to Fig. 2 with the parts thereof in a changed position;

55 Figure 4 is a horizontal plan sectional

view of the parts of my improved stop device located below the motor board of the phonograph;

Figure 5 is a vertical detail sectional view as taken on the line 5—5 of Fig. 4; 60

Figure 6 is a view similar to Fig. 5 with the parts thereof in a changed position;

Figure 7 is a detail sectional view as taken on the line 7—7 of Fig. 4;

Figure 8 is another detail sectional view 65 as taken on the line 8—8 of Fig. 4;

Figure 9 is a view similar to Fig. 8 with the parts in a changed relation;

Figure 10 is a perspective view of an actuating lever and associated pawl, embodied in my improved stop mechanism. 70

Referring now in detail to that embodiment of my invention illustrated in the accompanying drawings:—10 indicates the top wall or motor board of a phonograph, 11 indicates the turn-table, mounted upon the upright driven shaft 12, and 13 indicates the tone arm of the phonograph. The tone arm is pivotally mounted at one end 14 in a collar 15 fixed on the motor board to swing in 75 a horizontal plane, and extends down through said board to communicate with the amplifying horn, located below the motor board in the manner well known. The free end of said tone arm which overhangs the turn-table, is provided with the usual reproducer 16 which is adapted to carry a stylus 17. This stylus follows in the sound grooves 18 of a disc record 19 when applied to the turn-table 11. Said record as shown 80 herein is of the kind having an eccentrically disposed mute or non-playing groove 20 near its center, which communicates with the last or innermost sound groove 18 of the record and into which the stylus moves after 85 leaving the said last sound groove. 90

A short distance below the motor board is located a base board 21 upon which the major portion of my improved stop device is mounted. 22 indicates a plate mounted 100 on the base board and extending radially with respect to the turn-table driving shaft 12, and located within the peripheral plane of said turn-table. Arising from said plate is an upright flange 23 and spaced therefrom is a parallel rib 24, (see Fig. 4). Said upright flange and said rib provide a guide in which a block 25 is slidable. The block 25 has a shoulder 26 between its ends and adjacent said shoulder is a recess 27. A 110

lever 28 is pivoted between its ends as at 29 to the flange 23, and its bottom arm 30 extends into the recess 27 in said block 25. The top arm 31 of said lever extends up 5 through a slot 32 provided in the motor board and in a plate 33 on the top surface thereof. Operatively connected to the arm 31 and slidably on the plate 33, is a brake block 34 which carries a brake shoe 35 of 10 leather, adapted to engage the inner surface of the peripheral flange of the turn-table 11. On said plate 33 are spaced flanges or ribs 36, between which slides a trip bar 37. This bar has a stem 38 arranged in a position beyond the turn-table 15 so as to be easily actuated, as will more fully appear later. The trip bar 37 has a pin and slot connection 39 with the plate 33 so that it is capable of a limited longitudinal movement on said plate between the 20 ribs 36 thereon.

40 indicates a horizontally disposed lever which is pivoted at 41 to the upright flange 23. The short arm 42 of said lever has a 25 tooth 43 which is adapted to engage with the shoulder 26 on the block 25 as shown in Fig. 2, while the free end of the long arm 44 of said lever is made concentric with the axis of the tone arm 13. A spring 45 connects the plate 23 and long arm 44 together so that the tooth on the short arm is normally urged into engagement with the shoulder 26 of the block 25. A second spring 46 which connects the flange 23 and arm 30 of the lever normally acts to urge the block 25 away from the tooth 43 and to move the brake shoe 35 into engagement with the turn-table flange.

An arcuate plate 47 is fixed to the base 40 board 21, which plate is concentric with the axis of the tone arm 13. Said plate includes an upright web or flange 48, arranged adjacent the curved part 44 of the lever 40, and the top edge of said flange extends parallel 45 with the plane of said plate, except near one end where it is increased in vertical dimensions to provide a slight rise or hump 49. On the top surface of the plate 47 and spaced a short distance outwardly from the flange 48 is an arcuate ratchet toothed 50 bar 50.

To that part of the tone arm end 14 between the motor board and base board, is fixed a radial arm 51 which extends towards 55 and terminates near the flange 48. A block 52 is pivoted on the arm 51 by means of a screw 53. Said block is cut away on its underside to provide spaced shoulders 54 which engage opposite sides of the arm 51 and limit its rotation or pivotal movement with respect to said arm. To this block 52 is pivoted one end of a lever 55 by means 60 of a screw 56, so that said lever may swing in a vertical plane. The other end of said lever overhangs the long arm 44 of the

lever 40 and is adapted to ride on the top edge of the flange 48, and to said end of the lever is pivoted a pawl 57. Said pawl carries a tooth 58 at its free end to engage the ratchet teeth of the ratchet bar 50. On the lever 55, between its ends, is a laterally extending downwardly facing hook 59 which is adapted to hook over upon the end of the lever 51 connected to the tone arm as shown in Figure 8.

In use, my improved stop operates as follows: Assume that a record having an eccentric mute groove 20, has been placed upon the turn-table which is now rotating. The stylus 17 is next engaged in the usual manner with the starting sound groove of the record, the reproducer moving toward the center of the record in the playing thereof. As the reproducer thus moves, a swinging movement is imparted to the tone arm 85 and to the arm 51 which is connected thereto. As the arm 51 thus swings, the lever 55 will through the block 52 move with it. As said lever which rides on the top edge of the flange 48 approaches the rise or hump 49 it 90 is momentarily arrested so that the free end of the arm more closely approaches it when the lever 55 will ride the hump and be slightly elevated thereby, so that the tip end of the arm 51 will move under the hook 59 which will now engage or hook over upon said arm end. In the swinging movement of the tone arm and lever thus far the pawl 57 will drag over the teeth of the ratchet bar 50. In the further movement of the tone arm, as the reproducer approaches the last active sound groove 18 the lever 55 is supported by the arm 51 in a position above the adjacent end 44 of the brake lever 40, by reason of the hooked connection between 100 said lever 55 and arm 51 just above mentioned. When the stylus leaves the last sound groove at the center of the record, it will enter the mute groove 20 and will follow about said groove. By reason of the eccentricity of said mute groove, a short, sudden oscillation will be imparted to the tone arm in a direction opposite to that in which it has just been swinging. This will 110 impart a like movement to the arm 51, which will act to swing away from under the hook 59 on the lever, said lever being locked against following or moving with the arm 51 in this direction because of the engagement of the pawl 57 and tooth 58 with one of the teeth on the ratchet bar 50. With the lever thus locked and the arm 51 given a sudden short swing away from said lever, said lever is caused to yield upwardly 120 so that the end of the arm 51 is freed from under the hook 59 of said lever, as shown in Fig. 9. As said lever is thus left unsupported at its outer or pawl end, it will drop downwardly and strike the long curved arm 44 of the lever 40 and will depress the same.

When the lever arm 44 is depressed the short arm 42 will be elevated, disengaging its tooth 43 from the shoulder 26 of the block 25, when the spring 46 will act to swing the lever 28 into the position shown in full lines in Fig. 3, wherein the block 34 has moved outwardly until the brake shoe 35 engages the flange of the turn-table and stops the rotation of the same. In the outward movement of the block 34, the plate 37 is also moved outwardly, as shown in Fig. 3.

When the arm 51 has been given the short, sudden swing or oscillation in the reverse direction and it is released from the lever 55 which actuates the brake lever 40, as before mentioned, and because of the engagement of the pawl 57 with the ratchet bar, a change in angular relation or position occurs between the arm 51 and lever 55 due to the pivotal connection 53 between the arm 51 and block 52 and between said block and the lever 55, with the result that the tooth 58 of the pawl slips laterally off the rack 50 into the position shown in dotted lines in Fig. 3. When it is desired to play a new record, the tone arm is swung toward the periphery of the turn-table to clear the record just played, in the usual manner. As the pawl 57 is free from the ratchet bar 50 it in no manner interferes with this movement of the tone arm, but said tooth slides along the plate 47. A new record may be placed on the turn-table and the stem 38 is actuated to move the member 37 radially inward. The inner end of said member will engage the bar 34 and will move the same and the brake shoe 35 away from the flange of the turn-table, which now again rotates. As the bar 34 thus moves, it will through the lever 28 shift the block 25 to the right, when the tooth 43 of the lever 40 will engage behind the shoulder 26 of the block 25 and lock it in this position.

The tone arm is then swung inwardly so that the stylus may be placed in the starting groove of the record. In this last mentioned movement of the tone arm, the normal angular relation between the lever 55 and arm 51 is again established (due to the limited pivotal movement of the block 52) so that as said arm and lever move with the tone arm in the playing of the record the pawl swings into the plane of the ratchet bar so that the tooth 58 drags over said bar as before mentioned. When the lever 55 which slides over the edge of the flange 48 reaches the rise or hump thereon it momentarily stops and is elevated so the free end of the arm 51 engages under the hook 59 on said lever to again support the same when it clears said flange. When the stylus again reaches the eccentric groove, the arm 51 is released from under the hook on the lever 55, which, left unsupported, drops to en-

gage the lever 40 and release the brake block which again through its shoe, stops the rotation of the turn-table.

It is apparent that my improved stop mechanism need not be manually "set" with reference to the last sound groove of the record, and this no matter how far or how near radially said last sound groove is from the center hole in said record, but will automatically stop the rotation of the turn-table when the eccentric groove 20 or its equivalent therein is reached. It comprises but a few parts, which are all concealed from the view of the observer. Said parts are easy and simple to assemble and install in a phonograph and can not readily get out of order.

While I have referred to certain details of construction and arrangement of parts, I do not wish to be limited thereto except as may be pointed out in the appended claims.

I claim as my invention:

1. In a device of the kind described, the combination of a normally locked spring-pressed braking means, a horizontally swinging arm, a member adapted to be supported by and movable with said arm when swinging in one direction, said arm being adapted when moved in the other direction to release said member supported thereby, and said member being adapted to then release said normally locked braking means.

2. In a device of the kind described, the combination of a normally locked spring-pressed braking means, including a lever for releasing the same, a horizontally swinging arm, a member adapted to be supported by and movable with said arm when swinging in one direction, said arm being adapted when moved in the other direction to release said member supported thereby, and said member being adapted to then engage the lever of said braking means for releasing the same.

3. In a device of the kind described, the combination of a normally locked spring-pressed braking means, a horizontally swinging arm, a lever pivoted to said arm at a point between its ends so as to be capable of a limited independent movement in a horizontal plane and also a vertical movement, coacting means on the free ends of said arm and lever and providing a detachable supporting engagement for the lever with reference to said arm when said arm is moving in one direction, said coacting means on the free ends of said arm and lever being capable of detaching said lever from said arm when said arm is moved in the other direction, said lever when thus detached acting upon said normally locked braking means to release the same.

4. In a device of the kind described, the combination of a normally locked spring-pressed braking means including a lever for

releasing the same, a horizontally swinging arm, a lever pivoted to said arm so as to be capable of a limited independent movement with respect to said arm, said lever being supported by and movable with said arm when moved in one direction, a ratchet plate, a pawl carried by said lever and dragging over said ratchet plate when said lever is carried in one direction by said arm, said pawl and ratchet plate holding said lever against movement when said arm swings in the other direction, so that said arm is released from said lever which is then free to swing vertically under its own weight to engage said lever for releasing said braking means.

5. In a device of the kind described, the combination of a normally locked spring-pressed braking means including a lever for releasing the same, a horizontally swinging arm, a lever pivoted to said arm so as to be capable of a limited independent movement with respect to said arm, a plate having an edge upon which said lever slides when moved in one direction with said arm, said edge being constructed to cause a hooked engagement of said lever with said arm, so that said lever is supported by said arm after it has been moved beyond said plate, a pawl carried by the lever, a ratchet plate over which said pawl drags when said lever is moved in one direction by said arm, said pawl and ratchet plate holding said lever against movement with said arm when it moves in the other direction, so that said arm releases itself from the hooked connection with said lever, said lever being then adapted to engage the lever of the braking means to release the same.

6. In a device of the kind described, in combination with a phonograph having a tone arm and a turn-table adapted to receive a disc record provided with an eccentric mute groove at its center, a spring-pressed brake shoe member adapted to engage a part of the turn-table, means for releasably holding said brake shoe member out of engagement with said turn-table, an arm carried by the tone arm, and means associated with said arm carried by the tone arm for actuating said brake shoe releasing

means, said mute groove of the record acting through the tone arm and the arm carried thereby for causing said last mentioned means to release said brake shoe member holding means.

7. In a device of the kind described, in combination with a phonograph having a tone arm and a turn-table adapted to receive a disc record provided with an eccentric mute groove at its center, a spring-pressed brake shoe member adapted to engage a part of the turn-table, means for releasably holding said brake shoe member out of engagement with said turn-table, an arm carried by the tone arm, and means normally supported by and movable with said arm carried by the tone arm for actuating said brake shoe releasing means, said mute groove of the record acting through the tone arm and the arm carried thereby for producing a relative disengagement between said last mentioned means and its supporting arm so that said means will actuate and release said brake shoe member holding means.

8. In a device of the kind described, in combination with a phonograph having a tone arm and a turn-table adapted to receive a disc record provided with an eccentric mute groove at its center, a spring-pressed brake shoe member adapted to engage a part of the turn-table, means for releasably holding said brake shoe member out of engagement with said turn-table, an arm carried by the tone arm, a lever for actuating said brake shoe member releasing means, pivoted at one end to said arm between its ends and normally supported at its free end by the free end of said arm, said mute groove of the record acting through the tone arm and the arm carried thereby to release the free end of said lever which in turn acts to release said brake shoe member holding means.

In testimony that I claim the foregoing as my invention, I affix my signature in the presence of two witnesses, this 7th day of March, 1924.

HUGO F. SPENGLER.
